SEAL FOR CENTRIFUGAL SEPARATORS

George J. Strezynski, Poughkeepsie, N. Y., assignor to The De Laval Separator Company, New York, N. Y., a corporation of New Jersey

Application July 7, 1950, Serial No. 172,598

8 Claims. (Cl. 233—21)

1

This invention relates to centrifuges of the so-called "closed" type in which the material to be separated is supplied to the centrifugal bowl from a stationary feed pipe through a seal forming an air-tight path between the fixed pipe and an axial inlet passage of the rotary bowl. The invention has particular reference to an improved arrangement for feeding the material from the fixed pipe into the bowl of such centrifuges.

It is well known that the seal through which the stationary feed pipe is connected to the interior of the bowl in closed centrifuges undergoes considerable stress and wear due to the high speed at which the bowl rotates, the lateral vibrational movements of the bowl incident to its rotation, and the pressure at which the feed material is usually delivered to the bowl. To relieve such stress and wear on the seal, it has been proposed to provide the stationary feed pipe with a nozzle extending in close proximity to the entrance of the axial inlet passage of the bowl, so that the feed passes directly from the nozzle end of the pipe into the bowl passage, as disclosed, for example, in Forsberg Patent No. 2,145,541. In this way, pressure energy of the feed is converted into velocity energy as the feed passes through the nozzle, thereby reducing the pressure of the feed on the seal. However, while the use of such a nozzle reduces leakage and relieves the stress on the seal, it tends to impair the feeding operation by causing variations in the rate of feed to the bowl, which affect the separating operation and are therefore objectionable.

The principal object of the present invention is to provide a feeding arrangement for closed centrifuges, including a nozzle and seal, which overcomes the above-noted objection. A further object is to simplify the feeding arrangement for such centrifuges.

I find that the variations in the feed rate, when using the prior arrangement described above, are due to the fact that the axial feed passage of the bowl moves laterally or radially relative to the stationary feed pipe and its nozzle during rotation of the bowl. In fact, the usual mounting for the bowl allows for limited lateral movement of the bowl incident to its rotation. This lateral movement of the bowl causes its axial feed passage to move out of direct alignment with the nozzle on the feed pipe, thereby varying the back pressure in the feed pipe and the feed rate.

According to the present invention, the nozzle is aligned with the axial feed passage in the bowl but extends into the stationary feed pipe with an annular clearance space between the nozzle

2

and the wall of the pipe, whereby the nozzle is movable laterally relative to the pipe. A flexible sealing ring supports the nozzle in alignment with the bowl passage and forms a seal between the wall of the bowl passage and the wall of the stationary feed pipe. The sealing ring engages the bowl around its feed passage to cause the nozzle to partake of the lateral movements of this passage incident to rotation of the bowl. Consequently, the nozzle remains at all times in accurate alignment with the axial feed passage of the bowl, regardless of lateral deviations of the bowl axis relative to the feed pipe and the other stationary structure in which the bowl rotates.

The preferred form of the invention is as follows:

The sealing ring is generally U-shaped in cross-section so as to form annular concentric legs joined by a base portion of the ring. The inner leg constitutes a member in sealing engagement with an axial tube projecting from the bowl and forming the feed passage thereof. The nozzle is integral with the base portion of the ring, which supports the nozzle at the free end of the bowl tube. The outer leg of the ring constitutes a flexible annular flange extending outward from the sealing member and the nozzle and forming a means for securing them to the stationary structure to provide a seal between the wall of the stationary feed pipe and the wall of the bowl tube.

For a better understanding of the invention, reference may be had to the accompanying drawing, in which the single illustration is a vertical sectional view of a preferred form of the invention.

Referring to the drawing, the numeral 10 designates a centrifugal bowl adapted to be driven from the bottom (not shown) at high speed. At its upper part, the bowl is provided with a hollow tube or neck 10a projecting axially from the main body of the bowl. The bowl is mounted in the usual manner in lower bearings (not shown) to permit lateral movements of the upper part of the bowl and the tube 10a through a limited range.

The axial tube 10a forms a central feed passage 10b through which the material to be separated is delivered into the interior of the bowl. Radial ribs 10c are provided on the outer wall of the tube, around which a sleeve 10d is closely fitted. The sleeve and the ribs 10c form a series of outer passages in the tube, through which the clarified liquid is discharged from passages 10e

leading from the separating chamber of the bowl.

The bowl 10 is rotatable in a stationary structure having an upper part 11 supporting a ring 12. At its upper end, the ring 12 has an inwardly extending flange 12a surrounding the tube 10a but spaced therefrom. A cup 13 rests on top of the flange 12a and supports a sealing member 14 of rubberlike material. The member 14 is of annular form and is generally U-shaped in cross-section, the inner cylindrical portion engaging the sleeve 10d of the bowl tube and the outer cylindrical portion having an annular flat flange. The cup 13 conforms generally to the shape of that part of the seal 14 other than its inner tube-engaging collar portion. The seal 14 and its supporting cup 13 are clamped at their outer portions against the flange 12a by a hollow body 15, which is drawn downward against the stationary ring 12 by a nut 16. The clarified liquid from passages 10e is discharged above the sleeve 10d into a chamber 15a formed by the body 15. From the chamber 15a, which is sealed at the bottom by the annular member 14, the clarified liquid is discharged through an outlet 15b.

The material to be separated or clarified is fed to the bowl 10 through a stationary feed pipe 17 aligned with the tube 10a. Nozzle 18 is positioned at the free end of the tube 10a in alignment with the feed passage 10b of the bowl. The nozzle extends into the stationary feed pipe 17, and an annular clearance space 18a is provided between the nozzle and the pipe 17. The nozzle is supported by a sealing member 19 which, as shown, is in the form of a collar closely surrounding the tube 10a. A flexible annular flange 20 extends outward from the sealing member 19 and nozzle 18 and has a cylindrical part surrounding the member 19 in spaced relation thereto. An outwardly turned part 20a of the flange 20 is clamped between a shelf 15c of the body 15 and the lower end of an extension 17b of the pipe 17. The pipe sections 17 and 17b have interfitting conical end portions 17c forming a tight joint. A ring nut 22 is threaded on the upper portion of the hollow body 15 and engages a shoulder 17d of the pipe 17. By tightening the nut 22, the pipe sections 17 and 17b are urged together and the flange 20 is clamped against the shelf 15c.

In the preferred form of the invention, as illustrated, the nozzle 18, sealing member 19 and flange 20 are integral and are made of a rubberlike material, whereby the unit is flexible and elastic. More particularly, the parts 19 and 20 form a flexible sealing ring which is generally U-shaped in cross-section. The sealing ring, in effect, comprises annular concentric legs 19 and 20 joined by a base portion 21, from which the nozzle 18 extends. The nozzle 18 is of the Venturi type and has a passage 18b which tapers toward the entrance of the tube 10a and communicates with the interior of the annular leg 19. The latter is in sealing engagement with the wall of the bowl passage 10b. The smaller end of the nozzle passage 18b is spaced somewhat above the free end of the tube 10a and is considerably smaller in diameter than the space defined by the inner leg 19.

The operation of the device is as follows: By reason of the nozzle passage 18b, the pressure energy of the material fed through the stationary pipe 17-17b is at least partly converted into velocity energy as the material passes through

the nozzle. Accordingly, the pressure within the inner leg 19 is considerably reduced so as to allow a better seal between the member 19 and the wall of the bowl feed passage 10b. The member 19 not only forms part of the seal between the wall of passage 10b and the wall of pipe 17-17b but also, by reason of its engagement with tube 10a, causes the nozzle 18 to partake of the lateral movements of passage 10b incident to rotation of the bowl. It will be apparent, therefore, that the nozzle 18 will always be accurately aligned with the bowl passage 10b, regardless of lateral deviations of the bowl axis relative to the stationary structure including the parts 11, 12, 15 and 17. The outer leg 20, together with the clamping nut 22, constitutes the means forming a tight seal between the wall of the nozzle 18 and the wall of the stationary pipe 17-17b.

It will be apparent that the new feeding arrangement is of relatively simple construction. It forms an effective and durable seal between the stationary feed pipe and the axial feed passage of the bowl and operates to effect a reduction in the pressure of the feed on the sealing member 19 without, however, impairing the uniformity of the rate at which the feed is delivered to the bowl.

I claim:

30 1. In a centrifuge having a rotary centrifugal bowl and a stationary structure including a feed pipe for delivering material to the bowl, the combination of a hollow feed tube projecting axially from the bowl and rotatable therewith, the tube 35 communicating with the interior of the bowl and being movable laterally with the bowl incident to rotation thereof, a flexible sealing member in sealing engagement with the wall of the tube, the sealing member being adapted to partake of the lateral movements of the feed tube by reason 40 of the flexibility of said member, a nozzle member supported by said member at the free end of the tube and movable laterally with said member and the tube relative to the stationary structure, the nozzle forming between the stationary feed pipe and the tube, a passage which decreases in cross-sectional area toward the tube, and means for securing part of the sealing member to the stationary structure in fixed relation thereto to to form a seal between the wall of said pipe and the wall of the tube.

2. A combination according to claim 1, in which the nozzle and the sealing member are integral and are made of flexible elastic material.

55 3. A combination according to claim 1, in which said means include a flexible annular flange extending outward from the sealing member and nozzle, and a clamping element for securing the outer portion of said flange to the 60 stationary structure.

4. In a centrifuge having a rotary centrifugal bowl and a stationary structure including a feed pipe for delivering material to the bowl, the combination of a hollow feed tube projecting axially from the bowl and rotatable therewith, the tube communicating with the interior of the bowl and being movable laterally with the bowl incident to rotation thereof, a flexible sealing ring surrounding the tube and generally U-shaped in cross-section, one leg of the ring being in sealing engagement with the tube and the other leg being secured to the stationary structure, the ring having a base joining said legs, and a nozzle supported by the ring base at the free end of the 65 tube and extending into said pipe with an annu-

lar clearance space between the nozzle and the wall of the pipe, the nozzle and said first leg being movable laterally with the tube to prevent lateral deviation of the tube relative to the nozzle.

5. In a centrifuge having a rotary centrifugal bowl and a stationary structure including a feed pipe for delivering material to the bowl, the bowl having an axial feed passage for receiving material from the feed pipe, the combination of a nozzle aligned with said passage and extending into the feed pipe with an annular clearance space between the nozzle and the wall of said pipe, the nozzle being movable laterally relative to the pipe, and a flexible ring supporting the nozzle and forming a seal between the wall of said passage and the wall of the stationary feed pipe, the ring engaging the bowl around said passage to cause the nozzle to partake of lateral movements of the passage incident to rotation of the bowl.

6. For use in connecting an axial feed tube of a centrifugal bowl to a stationary pipe for feeding material into said tube, a flexible sealing ring having annular concentric legs, the inner leg forming a tube-receiving recess, the ring also having a base portion joining said legs, and a flexible nozzle integral with the ring and projecting from the base portion thereof in a direction opposite to the directions of said legs, the nozzle forming a passage communicating with said recess in the inner one of said concentric legs, said passage having at said base portion a smaller diameter than said inner leg.

7. For use in connecting an axial feed tube of a centrifugal bowl to a stationary pipe for feeding material into said tube, a flexible sealing ring having annular concentric legs, the inner leg forming a tube-receiving recess, the ring also having a base portion joining said legs, and a flexible nozzle integral with the ring and projecting from the base portion thereof in a direction opposite to the directions of said legs, the

nozzle forming a passage communicating with said recess in the inner one of said concentric legs, the passage tapering toward said tube-receiving recess and having at its tapered end the smaller diameter than said inner leg.

8. In a centrifuge having a rotary centrifugal bowl and a stationary structure including a feed pipe for delivering material to the bowl, the combination of a hollow feed tube projecting axially from the bowl and rotatable therewith, the tube communicating with the interior of the bowl and being movable laterally with the bowl incident to rotation thereof, a flexible sealing member in sealing engagement with the wall of the tube, the sealing member being adapted to partake of the lateral movements of the feed tube by reason of the flexibility of said member, a nozzle supported by said member at the free end of the tube and movable laterally with said member and the tube relative to the stationary structure, the nozzle affording communication between the stationary feed pipe and the tube and projecting from the sealing member into the stationary pipe with an annular clearance space between the nozzle and said pipe to accommodate said lateral movement of the nozzle, and means for securing part of the sealing member to the stationary structure in fixed relation thereto to form a seal between the wall of said pipe and the wall of the tube.
